GAS-GENERATING MEANS FOR EXPLOSIVE-ENGINES.

1,234,116.

Specification of Letters Patent.

Patented July 24, 1917.

Application filed April 17, 1914. Serial No. 832,574.

To all whom it may concern:

Be it known that we, GEORGE N. BARCUS, a citizen of the United States, residing at Wabash, Wabash county, and State of Indiana, and JOHN HOCKETT, a citizen of the United States, residing at Wabash, Wabash county, and State of Indiana, have invented and discovered certain new and useful Improvements in Gas-Generating Means for Explosive-Engines, of which the following is a specification.

Our invention relates to gas generating means for explosive engines, and its object is to provide means to enable kerosene to be employed as the motive fuel, to effect the complete vaporization of such a fuel by means of the exhaust gases, and to provide means whereby the vaporization is effected before mixture with the air necessary to form the explosive charge, and whereby the proper proportioning of such air with the vapor is automatically controlled.

With these ends and others in view, our invention is embodied in preferable form in the device hereinafter described and illustrated in the accompanying drawings.

In these drawings, Figure 1 is a side view in elevation of the device applied to an engine; Fig. 2 a central longitudinal section of the device; Fig. 3 a cross section on the line 3—3 of Fig. 1; Fig. 4 a detail view partly in section of the valve member; Fig. 5, a detail longitudinal section of the valve with sleeve removed; and Fig. 6 a detail cross section through the valve looking toward the head.

Referring to the drawings, the device comprises a shell, or body 1 which is provided with an inlet opening 2, adapted to communicate with a section of the exhaust pipe, and an outlet 3 which may be adapted to communicate with a section of the exhaust, or, as shown, may simply form the outlet and section of such exhaust means. The inlet 2 leads to a chamber 4 extending longitudinally of the shell. Within this chamber is mounted a longitudinally extending tube 6, which is closed at the end adjacent the exhaust inlet by means of a screw plug 7 and at the other end by a similar screw plug 8.

Within the tube 6, is loosely mounted a cylindrical solid core member 8, which is spaced by a thin film clearance space from the inner wall of the tube preferably by means of a head 9 at one end thereof and

radial studs 10 adjacent the other end. A kerosene inlet pipe 11 leads through the shell 1 and into the tube 6, near the end of the device opposite to that at which the exhaust enters, and the liquid fuel is thus admitted to the tube and caused to travel through the same between the core and the inner wall of the tube, thus spreading the liquid fuel in very thin tubular film over the surfaces of the core and wall of the tube thus providing an exceedingly large area of liquid fuel body relative to its mass and which body is adapted to be vaporized by the heat of the exhaust gases passing against the outside of the tube 6. The shell 1 is inclined to the horizontal, so that only a quantity of hydrocarbon in a liquid state determined by the height of the float chamber will enter the tube 6, and this liquid body will also be limited in amount and kept at a low level by the pressure of the gas generated in the tube above such level.

Hence there will always be a constant supply of liquid fuel in the lower part of the vaporizing tube and the feed to such tube from the gravity float valve tank will be independent of the suction of the engine. By this arrangement there will always be a surplus of vapor in the tube above the body of liquid, which surplus or accumulation is necessary to insure the proper formation of the rapidly successive charges of vapor drawn out by the suction of the engine. To insure that such accumulation shall be sufficient for more than one charge a collecting space is provided in the vaporizing tube beyond the end of the core as shown in the drawing.

Adjacent the hydrocarbon inlet end of the device, an air inlet passage 12 extends through the shell 1 into a chamber 13, which is formed by and between the wall of the shell and the wall of the exhaust tube 2. The chamber 13 is closed at the exit end of the shell by a cross wall 15. Near such exit end the air chamber or passageway 13 has a radial port 16 which opens into a mixing chamber 17, formed by a removable cap or casing 19.

The vaporizing tube 6 communicates near the exit end of the device with an outlet tube 20 which projects centrally through the port 16 and on this outlet tube 20 is mounted an automatically movable tubular valve member 22, which is provided with a series of longitudinal ports 23 formed by slots out

through the wall of the tubular member and which register at their ends with annularly disposed recesses 23' formed in the integral head 24 of the said tubular member. 5 These longitudinal port slots and recesses constitute vapor exit means to admit the vapor to the interior of the mixing chamber where the vapor is to be mixed with air to form an explosive mixture. An adjustable 10 threaded sleeve 25 surrounds the lower portion of the tubular valve member 22, and is provided with longitudinal slots 26 which correspond with the longitudinal port slots in the valve and by means of which, 15 through turning the sleeve rotatably, the area of the openings through the ports 22 may be increased or lessened in order to initially adjust the supply of vapor in proper proportion to the supply of air 20 drawn through the air passageway.

Fixed on or integral with the tubular valve member is a disk valve 27 which is adapted to close the outer end of the air port 16. As the valve 27 is drawn from its 25 seat, the air will be carried past the valve and into the mixing chamber to there mix with the vapor admitted through the ports in the tubular valve member.

The longitudinal ports in the tubular 30 valve member are slightly larger at their outer ends than at their inner ends, being preferably tapered toward their inner ends, the object of this arrangement being to permit a slightly greater volume of vapor to 35 be fed in at the initial operation of the engine, or when the same is running at slow speed.

Leading from the mixing chamber is an 40 outlet pipe 28, in which is mounted a butterfly throttle valve which is adapted to be controlled by any suitable manually operated means connected to the lever 29. The pipe 28 is adapted to communicate with the manifold of the engine.

45 The double valve member consisting of the tubular valve for the vapor and the disk valve for the air is adapted to be held to its seat by means of a spring 30, one end of which bears against the disk and the other 50 end of which is confined by the head of the casing 19.

The kerosene is preferably adapted to be fed to the inlet pipe of the device by gravity and the feed is controlled by an ordinary float valve in a casing 31 interposed between the tank and the device.

In the operation of the device the exhaust 60 gases are led through the tube 2 which forms a continuing section of the usual exhaust pipe, thus heating both the kerosene tube 6 and the outer air passageway 13. The kerosene is fed by gravity into the inlet 65 11, the quantity fed at each engine impulse being determined by the height of chamber 31, and thence passes to the tube 6

where it is caused to travel in a thin film between the core 7 and the inner surface of the wall of the tube. Owing to the extensive contact surface relative to the mass of the fuel afforded by the formation of this thin film, the kerosene will be instantaneously heated to a very high temperature and at once transformed into vapor. The rapidity of the formation of this vapor will be increased by the pressure within the tube 70 due to the fact that it is closed at the inlet end by its plug and at the other end by the spring pressed valve. Upon the suction impulse of the engine connected to the mixing chamber, air will be drawn into the 75 chamber or passageway 13 and will force open the double valve member and thus permit the vapor and the air to enter the mixing chamber and be thoroughly mixed. Upon starting the engine, a somewhat 80 greater volume of vapor proportional to the amount of air will be permitted to pass into the mixing chamber than when the engine is running at high speed, owing to the fact that the ports 23 are slightly wider at 85 their outer ends where they are first uncovered by the lifting of the valve on the outlet tube than at their inner ends, and also owing to the recesses 23', which open at 90 once upon the lifting of the valve from its rest. A greater suction of the engine will open the ports proportionately wider and admit a greater volume of vapor and also air, each in proper relative proportion.

The fixed opening area of the ports 22 95 may be adjusted by means of the outer cap or sleeve 25. Upon the exhaust impulse of the engine, the exhaust products will be carried through the chamber, and liquid hydrocarbon will be admitted into the lower 100 part of the tube 6. The air in chamber 13 will be heated, and the new charge of hydrocarbon vaporized by the heat of the exhaust.

Having thus described our invention, 110 what we claim is:

1. A device for forming a gaseous mixture for explosive engines for motor vehicles comprising an elongated tube open at both ends and which the exhaust traverses, an inner concentric tube entirely enclosed within said first tube and extending substantially the length thereof and having an inlet for liquid hydrocarbon alone adjacent one end thereof and an outlet for vapor 115 adjacent the other end thereof, a cylindrical elongated member within said second tube and extending from one end thereof, said member being separated from the inner surface of the hydrocarbon tube by a thin film 120 clearance space, and means providing for the accumulation of vapor charges.

2. A device for forming a gaseous mixture for high speed explosive engines for motor vehicles comprising an exhaust-heated 125

5 tube subject to the engine suction, a cylindrical body in said tube spaced from the inner surface thereof by a thin film clearance only, said tube having a vapor collecting space adjacent one end of the cylindrical body and means for feeding predetermined charges of liquid hydrocarbon to said tube independently of the suction.

10 3. A device for forming a gaseous mixture for explosive engines for motor vehicles comprising an elongated tubular exhaust receiving chamber, a concentric hydrocarbon receiving tube within said chamber, an elongated removable cylindrical bore-
15 choking core member mounted within said hydrocarbon tube and providing a narrow annular cylindric vaporizing space in said tube, means providing for the accumulation of vapor charges from the tube, and
20 means to admit liquid hydrocarbon to one end of said tube and a vapor outlet at the other end thereof.

25 4. A device for forming an explosive gaseous mixture for internal combustion engines comprising a tubular liquid hydrocarbon receiving body, a cylindrical member therein with a wall parallel to the wall of the tubular body and closely fitting the same and providing a narrow, annular elongated space, the cubical content of which is exceedingly small relatively to the surface areas of the tubular body and said member, said body having an outlet subject to the suction of the intake manifold of the
35 engine, means for feeding a limited amount of liquid hydrocarbon to said body independently of the suction, and means for passing the exhaust gases against the outside of said tubular hydrocarbon receiving body.

40 5. A device for forming a gaseous mixture for explosive engines comprising an exhaust receiving tube, a concentric liquid hydrocarbon receiving tube within the first tube and subject to the suction of the engine, a concentric cylindrical member within the second tube and separated from the wall of the latter by a thin cylindric clearance space only, and means providing for the accumulation of a charge of vapor in said
45 60 liquid hydrocarbon receiving tube between successive suction impulses of the engine.

55 6. In combination with a high speed explosive engine for motor vehicles, a device for forming an explosive mixture comprising a tubular body having means for admitting exhaust gases thereto, a tubular liquid hydrocarbon receiving body within said first body, an elongated cylindrical member within and concentric with said liquid receiving body, said member and inclosing body having closely contiguous walls parallel throughout the length of said member providing an exceedingly narrow restricted cylindric space between said walls of small
65 cubical content relatively to the surface areas

of said cylinder and inclosing tube, said device having a vapor-collecting space beyond the end of said cylindrical member and having an outlet therefrom, a mixing chamber beyond and in communication with said outlet having an air inlet, and suction controlled valve means for the vapor outlet and air inlet.

70 7. A device for forming a gaseous mixture for internal combustion engines comprising means forming an elongated restricted cylindrical space for the reception of liquid hydrocarbon, a tubular exhaust-heated body surrounding said means, said means having a vapor outlet subject to the suction of the engine, means to feed charges of liquid hydrocarbon of a predetermined amount to said space independently of the suction, a mixing chamber in communication with said space, means for admitting air to said chamber, and automatic spring pressed valve means controlled by the suction of the engine for controlling the admission of said vapor and air to said mixing chamber.

75 8. A device for forming a gaseous mixture for internal combustion engines comprising an exhaust-heated tube subject to the engine suction, and a cylindrical body in said tube spaced from the inner surface thereof by a thin film clearance and providing therewith a chamber for the accumulation of vapor charges, substantially as set forth.

80 9. A device for forming an explosive gaseous mixture for internal combustion engines, having a vaporizing chamber, which has communication with a source of liquid hydrocarbon, exhaust gas conveying means surrounding said chamber, a valve subject to the suction of the engine for closing the outlet end of said chamber, and means for mixing air with the vapor passing through said valve, substantially as described.

85 10. A device for forming an explosive gaseous mixture for internal combustion engines, having a liquid hydrocarbon receiving chamber, a heating chamber surrounding the hydrocarbon receiving chamber, a mixing chamber and a valve subject to the suction of the engine and between said hydrocarbon receiving chamber and said mixing chamber, substantially as described.

90 11. In a device for forming an explosive mixture for internal combustion engines, means forming a chamber for receiving liquid hydrocarbon, a heating chamber surrounding the first chamber, a mixing chamber, a spring pressed valve subject to the suction of the engine and between said mixing chamber and hydrocarbon receiving chamber, means associated with said valve having ports adapted to be covered and uncovered by said valve, said ports having a greater area adjacent the point of initial 105
115 120 125 130

opening of the valve than at the remaining portions of the ports, substantially as described.

12. In a device for forming an explosive mixture, in combination with means for vaporizing a liquid hydrocarbon, a mixing chamber in communication with said vaporizing means, air inlet means in communication with said mixing chamber, a valve controlling the passage of the vapor and having a port the area of which is greater at the initially opening portion of said port than at the remaining portion thereof, and means to uncover said ports to an extent proportionate to the suction of the engine, substantially as described.

13. In a device for forming explosive mixtures for internal combustion engines, in combination with means for vaporizing a liquid hydrocarbon, a mixing chamber, a vapor inlet tube leading into said chamber, air inlet means leading to said chamber, a tubular vapor inlet valve having ports extending longitudinally of the line of passage 25 of the vapor through the inlet tube, a head

closing one end of said valve and adapted to rest on the end of said inlet tube, said head having openings which communicate with said ports, substantially as described.

14. In a device for forming explosive mixtures for internal combustion engines, means for vaporizing a liquid hydrocarbon, means forming a mixing chamber, an inlet tube leading from said vaporizing means into said chamber, air inlet means leading into 35 mixing chamber, a common valve member for controlling said inlets, said valve having a tubular ported part surrounding the vapor inlet tube and having a disk valve controlling the air inlet, substantially as described. 40

In witness whereof, we have hereunto set our hands and seals at Wabash, Indiana, this 14th day of April, A. D., nineteen hundred and fourteen.
